Filed Mar. 5, 1964, Ser. No. 78,884

Claims priority, application Germany Sept. 10, 1963

Term of patent 14 years

(Cl. D14—3)

FIG. 3

FIGURE 1 is a perspective view of the automobile embodying my new design taken from the right front thereof; FIGURE 2 is a left side elevational view thereof; FIGURE 3 is a top plan view thereof; FIGURE 4 is a front elevational view thereof; and FIGURE 5 is a rear elevational view thereof.

The dominant features of my design are shown in full lines in the several views of the drawing.

I claim:

The ornamental design for an automobile, substantially as shown and described.
